Filed Oct. 7, 1953, Ser. No. 384,644
2 Claims. (Cl. 8—142)

Our invention relates to the art of dry cleaning of fabrics. It is particularly concerned with methods and equipment to insure maintenance of high cleaning efficiency of the dry cleaning solvent in a simple and effective manner.

In the usual process of dry cleaning fabrics, the soiled fabrics are subjected to the action of a volatile organic solvent which is immiscible with water as, for example, naphtha, Stoddard solvent, carbon tetrachloride, gasoline, benzene, trichlorethylene, and the like. Such solvents are effective for the removal of grease or oil stains as well as dust, dirt, lint and the like which commonly adhere to the grease and oil. It is conventional practice, in order to effect the removal of water-soluble stains, such as those caused by various foods and the like, to introduce into the volatile organic solvent in the washer a small proportion of water, usually of the order of 0.05%. This is commonly done by utilizing, in conjunction with the dry cleaning organic solvent, a small proportion of an oil-soluble dispersing agent which may, for example, be an oil-soluble higher fatty acid soap or other type of anionic, cationic or nonionic dispersing agent but is very commonly an oil-soluble synthetic organic detergent as, for example, long chain petroleum sulfonates such as the mahogany sulfonates; sulfated fatty alcohols, such as lauryl sulfate; long chain sulfoacetates, such as lauryl sulfoacetate; long chain alkyl sulfosuccinates such as dioctylsodiumsulfosuccinate; higher fatty acid monoglycerides such as mono-olein; higher fatty acid monoglyceride sulfates, such as mono-olein mono-sulfates; and the like, the sulfates and sulfonates being used in the form of salts. In the presence of such dispersing agents, the water added to the dry cleaning volatile organic solvent is very finely or colloidally dispersed or emulsified throughout the solvent so as to form what is apparently, to the naked eye, a homogeneous composition or what may be characterized as a pseudo solution. While the advantages of the addition of water to a water-immiscible dry cleaning organic solvent and the solubilizing or emulsifying of the water by means of an oil-soluble dispersing agent have been, broadly speaking, heretofore known and used, the full potentialities of such existing knowledge have not been utilized in practice because of the failure to understand certain aspects of the criteria which govern the conditions under which the dry cleaning operation is best practiced. Thus, for instance, as almost invariably practiced today, the amount of water added to the water-immiscible dry cleaning solvent is based upon the weight and nature or condition of the fabrics added to the washer, a situation which is affected, among other things, by the relative humidity in the atmosphere and by other factors. The real key to the matter of insuring uniform superior dry cleaning in modern reclamation systems lies in the discovery which we have made, as will be explained in detail below, of the relationship and significance of electrical conductivity and the control and maintenance of the conditions which account for certain minimum electrical conductivity essential for the securing of the aforesaid results.

In the dry cleaning operation proper, utilizing such substantially clear homogeneous emulsions, when the soiled fabrics are contacted with the dry cleaning emul-

2

sion in the so-called washer or wheel, the fabrics absorb a certain amount of such water from the dry cleaning emulsion, the amount of such absorbed water depending upon the nature and condition of the fabrics. The remaining moisture in the dry cleaning organic solvent emulsion remains more or less constant during the cleaning operation of that particular batch of clothes. However, when a new batch of clothes or fabrics is introduced into the washer and is contacted with such dry cleaning organic solvent emulsion, an additional amount of the water dispersed therein is abstracted or absorbed by the clothes or fabrics. The result is that in the dry cleaning operations conducted by any plant the moisture content of the volatile organic solvent emulsion varies quite considerably from batch to batch of soiled fabrics and, at various stages of the use thereof for the cleaning of different batches of clothes or fabrics, the moisture content drops to a point where it is inadequate to serve its intended purposes, and the cleaning results are non-uniform.

In the dry cleaning step proper, as carried out in the so-called washer or wheel, it has been the practice to utilize various concentrations of oil-soluble soaps or detergents as, for example, from a small fraction of one percent to as high as seven percent or even higher. During the cleaning of various batches of clothes, the concentration of the soap or detergent decreases and it has, therefore, been the practice to replenish the soap or detergent content from time to time.

Despite all of such prior knowledge and practices, serious difficulties and lack of significant knowledge have existed so that, from a practical standpoint, it has not been possible for the operator of a dry cleaning establishment to carry out the dry cleaning operations in such a manner as to obtain uniform substantially optimum results from batch to batch of fabrics being cleaned.

We have discovered that outstandingly satisfactory uniform cleaning results of high efficiency can be obtained in a simple, safe and practical manner by procedures which may readily be understood and practiced by the average operator of a dry cleaning establishment. Our invention is based, in part, on the discovery that, in dry cleaning with water-immiscible organic solvent emulsions containing an oil-soluble dispersing agent or dry cleaning soap or detergent and water, as more particularly described below, the electrical conductivity of such emulsions should be maintained at not less than about 10×10^{-7} mhos to insure uniformly superior over-all results with respect to removal of inert soil, water-soluble soil, prevention of soil redeposition, whiteness retention, avoidance of deleterious action on fabrics, economy of detergency consumption, and freedom from interference with proper operation of the filtration and distillation systems. The amount and type of dry cleaning dispersing agent or detergent and the amount of water influence the degree of electrical conductivity imparted to the dry cleaning water-immiscible organic solvent. However, the state of distribution of the water is also a very important factor. In all cases, for the effective practice of our invention, the water must be so finely or colloidally dispersed in the organic solvent as to produce a substantially clear homogeneous emulsion, so far as the naked eye is concerned, or what may be characterized as a pseudo solution. In this connection, it may be noted that it is entirely possible to provide mixtures of water-immiscible organic solvents and oil-soluble dispersing agents and water, identical in proportions such as we have found to be especially effective as hereafter described, and still be unsatisfactory for our purposes because their electrical conductivity falls appreciably below the aforesaid value of 10×10^{-7} mhos due to the fact that the

water is not properly distributed through the organic solvent. Hence, it will be understood that when we speak herein of emulsions containing oil-soluble dispersing agents or detergents and water, it will be understood that we mean such emulsions wherein the water is so finely dispersed as to form a substantially clear homogeneous emulsion in the water-immiscible organic solvent, as viewed by the naked eye. It is also important, for the most effective practice of our invention, that the entire system to be charged with water so that the emulsified water passes through the filter.

Our invention is also based, in part, on a procedure, and simple and effective equipment for use therein, involving determining the electrical conductivity of the aforesaid dry cleaning emulsions at periodic or non-periodic intervals and if, during use of such emulsions in the cleaning of a batch or successive batches of soiled fabrics, the electrical conductivity has dropped to appreciably below 10×10^{-7} mhos an amount of water and/or oil-soluble dispersing agent or dry cleaning detergent is added to the emulsion so as to bring the electrical conductivity thereof to not less than the aforesaid minimum value thereof.

Our invention is particularly advantageously practiced with the utilization, as the oil-soluble dispersing agent, of sulfate and sulfonate detergents containing an alkyl group of at least 8 carbon atoms and usually between 8 and 18 carbon atoms, in the form of salts thereof as, for instance, the alkali metal, ammonium and amine salts. In addition to the examples thereof described above, salts of higher alkyl aryl sulfonates such as dodecyl benzene sulfonate, octyl benzene sulfonate, nonyl naphthalene sulfonate, keryl benzene sulfonates, and the like can be utilized. It is also particularly advantageous, in the especially preferred embodiments of our invention, to utilize proportions of oil-soluble dispersing agent or detergent, on the non-volatile basis, of not less than about 1.5%, based on the volume of the organic solvent, and desirably within the range of about 1.5% to about 3%, a good average being about 2%. In this connection, it will be understood that dry cleaning detergents are commonly marketed in the form of liquid or paste products and frequently contain diluents, volatile ingredients and the like over and above the non-volatile dry cleaning detergents proper. When we speak of, for example, 1.5% to 3% of the dry cleaning detergent, said percentages are on the non-volatile active detergent basis.

The amount of water added to the water-immiscible dry cleaning solvent should, in the particularly preferred embodiments of our invention, not be appreciably less than 0.2%, by volume, and most desirably ranges from about 0.2% to about 0.4%, it being relatively uncommon that this latter figure will be exceeded. So far as actual dry cleaning practice goes, these amounts of water are abnormally large but their use, under the conditions of the present invention, has been found to be most advantageous, cleaning of the fabrics being enhanced and subsequent spotting operations being reduced to a substantial minimum.

The optimum conditions under which the dry cleaning operation should be conducted, taking into account the over-all aspects, therefore, will, in general, involve the utilization of a water-immiscible dry cleaning organic solvent emulsion containing from about 1.5% to about 3%, with a good average of about 2%, of an oil-soluble sulfate or sulfonate detergent containing an alkyl group of at least 8 carbon atoms, and from about 0.2% to about 0.4%, with a good average of about 0.3%, of water, the electrical conductivity of said emulsion being not less than about 10×10^{-7} mhos.

In the light of the foregoing description, it will be understood that, in the case of the foregoing dry cleaning organic solvent emulsions, the electrical conductivity varies more or less uniformly as a function of the water and detergent content of such emulsions, the greater the

water and detergent content, at least within practical operating ranges, the greater the electrical conductivity. Within any given system utilizing a particular water-immiscible dry cleaning organic solvent, a particular detergent and water, a substantially fixed relationship exists with respect to the variability of the electrical conductivity as a function of the quantity of detergent and water, particularly the latter, dissolved or colloidally dispersed in the organic solvent in the form of the aforesaid emulsions. Thus, with any given system, for example, one utilizing Stoddard solvent as the dry cleaning organic solvent, dioctyl sodiumsulfosuccinate as the dispersing agent or detergent, and distilled water as the source of water, it is possible to plot curves showing the relationship of electrical conductivity to detergent and water content, particularly the latter, within practical limits of the latter. Other curves can readily be prepared based upon electrical conductivity data utilizing any specific system of materials.

It will be understood that through continued use of the dry cleaning emulsion on different batches of soiled fabrics, said emulsion builds up a constantly varying amount of soluble impurities which affect to a greater or lesser extent, depending upon the amount and nature of such impurities, the electrical conductivity of said emulsion. Ordinarily, this is not sufficient substantially to affect adversely the conductivity readings so far as their reflecting the condition of the emulsion with respect to the content of water and detergent therein. In the usual case, the electrical conductivity readings of an emulsion containing a relatively high proportion of soluble impurities resulting from long continued use of the emulsion prior to distillation thereof will show a somewhat lower conductivity than a similar pure organic solvent solution containing only the same amounts of oil-soluble detergent and water. Suitable extrapolations can be resorted to, if desired, in situations of this kind, if deemed advisable, to take into account the effect of soluble impurities on the electrical conductivity of repeatedly used dry cleaning emulsions.

While satisfactory results are obtained with electrical conductivities maintained at not less than about 10×10^{-7} mhos, we prefer to operate at higher levels as, for example, from about 40 to about 120×10^{-7} mhos or even higher, a particularly preferred range being from about 50 to about 100×10^{-7} mhos.

In the preferred manner of carrying out the present invention, in the so-called "two bath" system, for example, in dry cleaning systems which include a washer-filter-trap assembly reserved for the detergent emulsions and a separate rinse and filter system, and wherein said emulsion is continuously circulated through said washer-filter-trap assembly, the water-immiscible liquid organic solvent is activated with the requisite amount of oil-soluble non-volatile dry cleaning dispersing agent or detergent and the resulting solution is circulated through said assembly to effect uniform distribution of said dispersing agent or detergent throughout the entire body of organic solvent in the assembly. The requisite amount of water is then added and the resulting mixture is circulated through said assembly whereby to solubilize or emulsify the water throughout the system, so that the solubilized or emulsified water emulsion passes through the filter, and forms a substantially clear homogeneous composition having an electrical conductivity not less than about 10×10^{-7} mhos. The soiled fabrics to be dry cleaned are then subjected to the resulting dry cleaning emulsion in the usual way, successive batches of soiled fabrics being dry cleaned. The electrical conductivity of the emulsion is measured, for instance, from time to time, and, if the electrical conductivity has dropped to below the aforesaid value, an additional amount of water and, if necessary, detergent is added to bring the concentration of the water and detergent and the electrical conductivity of the emulsion to within the predetermined ranges. It will, of course, be

understood that after the fabrics are cleaned they are rinsed and dried and fluffed in accordance with standard practices in the art.

It will be understood that the addition of oil-soluble dispersing agent or detergent to the organic solvent emulsions will occur far more infrequently than the additions of water. In this connection, it will be appreciated that the solubility and stability of the oil-soluble dispersing agent or detergent are such that the content thereof diminishes quite slowly so that replenishing thereof is necessary at only relatively sporadic intervals. Hence, when the electrical conductivity drops below about 10×10^{-7} mhos it will, in most cases, be necessary to add only water in order to increase the electrical conductivity to a value above said minimum figure. The content of oil-soluble detergent in the dry cleaning emulsion can be determined from time to time by heretofore known procedures. It may be found, in certain instances, that when the electrical conductivity drops below the aforesaid minimum value there may be a deficiency of both detergent and water, and, in such cases, both detergent and water will be added to bring the amounts thereof within the desired or predetermined ranges as well as restoring the electrical conductivity of the dry cleaning emulsion to a value not below said minimum figure. In the usual case, however, as stated, water additions alone will be sufficient and the detergent content can be determined and maintained at desired proportions by procedures already known in the art.

In the drawing, FIG. 1 illustrates a conventional type of dry cleaning system, except as pointed out below, showing only the cleaning system in schematic form and wherein the usual washer-filter-trap assembly is utilized, the rinse system being omitted since it is strictly conventional and forms no part of our present invention although, of course, it will be understood that the rinse system is utilized after the cleaning operation is completed. In FIG. 1, we show a simple unit which is utilized in the practice of the method of our invention.

FIG. 2 is a vertical section through the unit or device for determining the electrical conductivity of the dry cleaning emulsion.

FIG. 3 is a perspective view of the electrodes and supporting structure.

In FIG. 1, numeral 10 represents a conventional type of dry cleaning washer or wheel connected through drain pipe 12 to the usual trap 14, pump 16 and filter 18. Connected into the line between the filter and wheel is the conductivity measuring device 20, hereafter described in detail. As shown in FIG. 1, the device 20 is shown positioned in the direct line between the filter and the return line to the washer in which case all of the filtered solvent passes through said device. If desired, however, said device 20 can be positioned in a by-pass line so that the filtered solvent will not pass through said device 20 except when an actual conductivity test is to be carried out.

The device 20 shown in FIGS. 2 and 3 provides a simple, effective means which enables the dry cleaner readily to determine the electrical conductivity of his dry cleaning emulsions at any desired stage of his operation. It comprises a chamber 22 open at its top and provided with a cover 24. Connected into the chamber 22 adjacent its top is an inlet pipe 26 through which the dry cleaning emulsion is admitted to said chamber 22. A flexible tube 28 made of a material, such as "Neoprene," which is resistant to the action of organic solvents, leads toward the bottom of the chamber. The pipe 26 is provided with a valve 30. A pipe 32, serving as an outlet from the chamber 22 connects into the bottom of the chamber and joins, through a valve 34, a T 36. Extending from the T is an outlet pipe 38 and overflow pipe 40, the open top of said overflow pipe being disposed just above the top of the electrodes.

The electrode assembly, denoted generally by numeral 42, is adapted to be inserted and removed from the cham-

ber 22 and is so constructed as to rest in said chamber against movement. It comprises a plurality, preferably three in number, of electrodes, 44, 46, 48, which may be brass sheets or plates about 6 inches square supported in a frame made of a suitable insulating material as, for instance, "Lucite" or polystyrene. The frame comprises side members 50, 52 which are provided with notches 54, 56 in which opposite edges of the electrodes fit. The electrodes are supported and fixed in vertical position by bottom and top members 58 and 60 respectively. Reinforcing members 62, 64 are provided on opposite sides of the side members to impart strength and rigidity to the frame. The transverse plates 66 and 68 serve to hold the electrode assembly against tipping in the chamber 22. Vertical extension pieces 70, 72 provide convenient grasping means for lifting the electrode assembly out of the chamber, and they serve also to rest against the underside of the cover to aid in holding the assembly in position against movement. Electrodes 44 and 48 are electrically connected by wire 74 the ends of which may be soldered to said electrodes. Wire leads 76, 78, connected to electrodes 46 and 44 respectively, pass through grommets 80, 82 in the cover 24, and are adapted to be connected to an electrical conductivity meter or measuring device (not shown) of any suitable type.

Although we have described a system wherein the required additions of water and detergent are made, for instance from time to time, by what may be called manual means, it will be seen that, if desired, equipment can be so arranged as to automatically measure the electrical conductivity of the dry cleaning emulsion and automatically control the addition of water and/or detergent in response to changes in electrical conductivity of the emulsion. This can readily be accomplished by the utilization of a measuring device wherein changes in the electrical conductivity of the emulsion during the subjection of the fabrics to the action thereof during the dry cleaning operation are determined and, when the electrical conductivity falls below a predetermined value, valve means are opened to admit water and/or detergent, particularly water, to the washer so that it is admixed with the dry cleaning organic solvent emulsion to bring the detergent and/or water content up to the desired value. When such value is reached, in response to the increase in the electrical conductivity resulting from such increased detergent and/or water content, the valve means close and the supply of detergent and/or water is shut off.

The electrical conductivity values referred to above and in the claims represent the reciprocal of resistance values in ohms obtained when using the herein described cell with brass plates measuring $6 \times 5\frac{1}{2}$ inches spaced 0.150 inch apart and a standard ohm meter which employs a potential of 60 volts D.C. It will be appreciated that, with different types of cells and different cell constructions, different values may be obtained and such values may be reflected in terms of electrical conductance, electrical conductivity or electrical resistance. In any event, however, whatever the values may be and whatever the unit of measurement may be, to the extent that such values correspond to the herein disclosed and claimed electrical conductivity values obtained by measurement with a cell made as described above, they will, of course, fall within the scope of our present invention. We prefer to recite the values in terms of electrical conductivity for simplicity purposes since these values increase with addition of water as disclosed in detail hereinabove.

This application is a continuation-in-part of our prior application Serial No. 328,898, filed December 31, 1952, now abandoned.

What we claim as new and desire to protect by Letters Patent of the United States is:

1. In the dry cleaning of soiled fabrics, the steps which comprise cleaning successive batches of said fabrics with a water-immiscible dry cleaning liquid organic solvent containing (a) from about 1.5% to about 3% of an oil-solu-

ble non-volatile dry-cleaning water-emulsifying detergent and (b) from about 0.2% to about 0.4% of water so finely emulsified in said organic solvent as to form a substantially clear homogeneous emulsion, said emulsion having an electrical conductivity between about 10 and about 120×10^{-7} mhos, periodically measuring the electrical conductivity of said emulsion and, when said electrical conductivity drops below said lower aforesaid value, measuring the emulsifying detergent content of said emulsion, adjusting said emulsifying detergent content to bring it to within the aforesaid values, and, to the extent required to bring the electrical conductivity of said emulsion to within the aforesaid values, adding water in the requisite amount.

2. In the dry cleaning of soiled fabrics, the steps which comprise cleaning successive batches of said fabrics with a continuously circulating filtered water-immiscible dry cleaning liquid organic solvent containing (a) from about 1.5% to about 3% of an oil-soluble dry cleaning water-emulsifying detergent selected from the group consisting of sulfate and sulfonate detergents containing an alkyl group of at least 8 carbon atoms, and (b) from about 0.2% to about 0.4% of water so finely emulsified in said organic solvent as to form a substantially clear homogeneous emulsion, said emulsion having an electrical conductivity between about 50 and about 100×10^{-7} mhos, measuring the electrical conductivity of said filtered emulsion and, when said electrical conductivity drops below said lower aforesaid value, measuring the detergent content of said filtered emulsion, adjusting said detergent content to restore it to within the aforesaid values, and add-

ing water in the requisite amounts to restore the electrical conductivity of said filtered emulsion to within the aforesaid values.
